METHOD OF EXPANDING BRAKE DRUMS

James F. Strnad, Bedford, Ohio, assignor to
Lempeo Products, Inc., Bedford, Ohio, a corporation of Ohio

Application July 2, 1932, Serial No. 620,601

3 Claims. (Cl. 29—152.2)

This invention relates to a method of expanding automobile brake drums and the like.

The principal object of the invention is to provide for such expansion with a much smaller size machine than is required when present methods and equipment are employed. While the following description has special reference to the expansion of brake drums for the purpose of inserting reinforcing wear rings, it will be understood that the invention is susceptible of being carried out for the accomplishment of other purposes and that apparatus of different construction can be employed for carrying out the process disclosed.

15 A further object of my invention is to provide for the deformation of the metal of the brake drum in a plurality of easy stages whereby to reduce the chance of weakening the metal by too rough treatment.

20 A further object is the provision of a process which lends itself to performance by mechanism of the simplest construction and minimum number of working parts.

Other and more limited objects will be apparent from the following description when taken in connection with the accompanying drawings in which Fig. 1 is a fragmentary sectional view showing the mechanism employed in connection with my improved process in the position assumed just as the last stage is completed; Fig. 2 is a section on the line 2—2 of Fig. 1; Fig. 3 is a section through a brake drum showing the reinforcing wear ring in position; Figs. 4 to 7 inclusive are fragmentary sectional views 25 indicating successive steps in the process showing the position of the parts and the operations performed; and Figs. 8 to 11 inclusive are similar views showing a modified form of my improved process being carried out by the use of a slightly different apparatus, Fig. 11 indicating the completed product.

30 Referring now to the drawings, the apparatus will first be described. The numeral 10 indicates the lower end of the plunger of a power press, preferably a hydraulic press, which may be of conventional construction and is therefore not illustrated and 11 indicates a fragment of the base thereof or any fixed stationary member. Seated within a depression in the member 11 is a die member 12 of annular form and conforming to the exterior of the brake drum in its final shape. Attached to the plunger 10 by any suitable means not shown is a block carrying member 13 provided with a frusto conical downwardly extending projection 14 and internally

threaded openings 15 receiving a plurality of headed studs 16. Received on the studs 16 are sector shaped blocks 17 having inner surfaces adapted to engage the conical outer surface of the projection 14 and provided with radially elongated openings 18 adapted to allow motion of the blocks 17 radially with respect to the projection 14. The openings 18 are shouldered whereby to allow a considerable vertical motion of the blocks with respect to the member 13 axially of the studs 16, such motion being limited in a downward direction by the engagement of the head 16a with the inwardly extending flange 18a at the top of the block 17.

It will be observed that the main portion of the opening 18 has a radial dimension as much greater than the diameter of the head 16a as the radial motion of the block with respect to the projection 14 is intended to be. The smaller upper portion of the opening 18 bears the same relation to the shank of the stud 16. At the top and bottom of each of the blocks 17 is a circular groove 19 of L-shaped cross section. Received in the grooves of all the blocks are split rings 20 which urge the blocks inwardly into engagement with the projection 14. The sector shaped blocks 17 are, as is obvious from Fig. 2, slightly spaced from each other and form altogether substantially a complete ring. The spacing between them permits radial motion with respect to the projection 14. The outer surfaces define a generally cylindrical surface, substantially the lower third of which in the embodiment shown in Fig. 1 is formed by a bevel 21.

It will be obvious that when the plunger 10 is drawn up from the position shown in Fig. 1 that the blocks 17 will ride downwardly with respect to the member 13 under the influence of gravity and the action of the split rings 20 until the head of the stud 16 engages the flange 18a, the blocks riding inwardly whereby to decrease the diameter of the surface defined by the outer surfaces of the blocks. Obviously, when the blocks are thus in down position they can be inserted into a brake drum or similar member of a diameter smaller than would accommodate them if they were in up position with respect to the member 13. It is also obvious that when the blocks are in down position and the plunger of the press is lowered, when the blocks are constrained against motion with the block holding member 13, they will begin to move radially under the wedging action of the projection 14.

The form of the apparatus shown in Figs. 8 to 10 inclusive is identical with that just described

except that the bevel portion 21 is omitted, the outer surface of the blocks being thus cylindrical from top to bottom.

In Fig. 4 I have shown the brake drum before any deformation has taken place and with the apparatus in the position assumed just as deformation is about to begin. It will be seen that the blocks 17 are in down position with respect to the member 13 and that most of the beveled portion of the blocks is within the flange 22 of the brake drum. These blocks are of such size that when the major part of the beveled portion is within the drum flange 22, it will engage such flange whereby to constrain downward movement of the blocks. Further downward movement of the member 13 under the influence of the plunger 10 will result in radial or expanding motion of the blocks. When the member 13 has been forced to full down position, the parts will occupy the relations shown in Fig. 5. Here it will be seen that approximately the upper third of the flange 22 is flared outwardly. The plunger is then moved upwardly and again lowered, the parts assuming the relation seen in Fig. 6 when the blocks 17 have entered the flange 22 to about two thirds its depth, further downward motion of the blocks being prevented in the same way as in the first stage. The plunger is again brought down and the parts assume the relations seen in Fig. 7, the second third of the flange 22 being flared outwardly and the first third being operated upon by the cylindrical upper portion of the block 17 to impart thereto a cylindrical shape. The plunger is again retracted and brought down, this time entering to the full depth of the flange and resulting in flaring the last third and imparting cylindrical shape to the upper two thirds as shown in Fig. 1. It is within the contemplation of my invention to operate upon a drum which has been shaped as shown in Fig. 1 by a die having blocks such as shown in Fig. 8 whereby to impart cylindrical shape to the last or bottom third thereof. But this is not necessary since a ring 24 of the shape shown in Fig. 3 may be employed as well as one of the shape shown at 25 in Fig. 11.

While I prefer to carry out my invention in the steps just described, I may successfully employ blocks 26 not having the bevel 21 and constrain their downward movement beyond the desired point by the use of stops adapted to be engaged between said blocks and some member fixed with respect to the drum flange 22. These stops may take the form of rings 27 and 28 of different widths for the different steps or suitable projections may be formed on the blocks and engage some member fixed with respect to the die portion 12. In Fig. 8 I have shown the parts in the relation assumed just prior to deformation of the first zone of the flange 22, the block 26

being engaged against the ring 27 for prevention of further downward motion of the blocks 26.

In Fig. 9 I have shown the position of the parts and the shape of the flange 22 after the plunger has been urged down. Here it will be seen that a cylindrical shape is imparted to the first zone on the first operation. After this operation has been accomplished, the plunger is drawn up and the ring 27 is substituted by one 28 of substantially half the width, the plunger is again brought down until the blocks 26 engage the ring 28 whereupon the parts will assume the relations shown in Fig. 10. The plunger is then forced fully down resulting in imparting a cylindrical shape to the upper two thirds of the flange 22. The ring 28 is then removed and the process repeated whereupon the flange 22 is shaped as shown in Fig. 11. The reinforcing and wear ring 25 may then be inserted.

While I have shown and described preferred embodiments of my invention, I wish it understood that the same is not limited to the details shown and described but only in accordance with the spirit and scope of the appended claims.

Having thus described my invention, what I claim is:

1. The process of expanding a brake drum flange which comprises expanding the same in a series of reciprocations of a reciprocating operating element of a radially expandable expanding die proceeding from the open end toward the bottom and deforming a portion only thereof on the first reciprocation and on the second reciprocation producing initial deformation of a second portion and further deformation of the first portion.

2. The process of expanding a brake drum flange for insertion of a reinforcing wear ring by means of a radially expandable expanding die having a reciprocating actuating element for causing radial expansion of said die which consists in expanding on the first reciprocation a portion only of said flange adjacent the open end thereof, an outward flare being imparted to said portion, and upon the second reciprocation expanding an additional portion, an outward flare being imparted thereto, and imparting to said first portion a cylindrical shape.

3. A method of expanding brake drums by the use of a radially expandable expanding die having a reciprocating actuating element which includes expanding an outer annular portion of the braking flange of said drum by an initial stroke of said actuating element and then expanding an adjacent annular portion of said flange to the same diameter as said first annular portion by a subsequent stroke of said actuating element.
